Theodore W. Lillagne, of Philadelphia, Pa.

Assignor to Savery Co. of same place.

Letter Patent No. 1222, dated April 3, 1860.

The schedule referred to in these Letters Patent and making part of the same.

To all, whom it may concern:

Be it known that I, Theodore W. Lillagne, of the City of Philadelphia, and State of Pennsylvania, have invented or produced a new and original design, for Fire-Dogs; and I do hereby declare that the following is a full, and exact description of the same, reference being had to the annexed drawing, making a part of this specification, and to the letters of reference marked thereon.

For the purpose of nominal distinction, I call this design for fire-dogs, 'The Shell Pattern'. It consists of a combination of ornamented scrolls supporting a shield, and surmounted by an open, oval frame, ornamented with shell-work and leaves, as hereinafter described - the same being arranged to produce the general form and outlines shown in the drawing, to be cast in metal to serve as the front part of a fire-dog.

The scrolls A. A'. A². A³. constitute together a group, on each side, to form the two legs of the fire-dog, the scrolls A. & A', being ornamented, on their outer

2.

Dec. 1222

edged with the shell work 1-1, and upon these two groups rests the shield B, whose upper part bears the horizontal branches 2-2, and terminates in the rising leaf 3. On each side of this shield, (B) are the body scrolls 1.1, 2.2, ornamented and connected with the branches, 2-2, of the shield (B) as seen in the drawing. Upon the upper end of these body scrolls 1.1, 2.2, rest the reversed scrolls D.D., and upon the upper ends of these and the upper termination, 3, of the shield (B), rests the open, oval frame E, which is ornamented around its outer edge by the shell work 4-4, and the leaves 5 & 6. The whole being arranged together as seen in the drawing.

What I claim as my invention or production, and desire to secure by Letters Patent is -

The configuration and ornamentations arranged and combined together as herein described and set forth, as a new and original design for a fire-dog.
